UNITED STATES PATENT OFFICE.

MAXWELL ALPERN, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA.

STOKER CONSTRUCTION.

Application filed April 4, 1922. Serial No. 549,456.

One object of this invention is to provide a relatively simple, durable and economical form of underfeed stoker characterized by the inclusion of suitably formed plates movable between the retorts and the dumping plates, for assisting in the rearward movement of fuel and ash, without delivering or permitting the delivery of air thereto.

It is further desired to provide a stoker of the type noted with imperforate reciprocating or rocking extension plates designed to eliminate the use of and necessity for the air openings and avoiding the sifting through said openings of fine fuel and ash which has hitherto interfered with the operation of apparatus of the same general class.

A further object of the invention is to provide a stoker of the above type with a novel combination of alternated movable plates and immovable extension grates; the arrangement being such that the grates shall be substantially in the line of the retorts while the imperforate plates in the lines of the tuyères shall be movable in order to assist the rearward movement of fuel and ash at those points where such movement would otherwise be sluggish or insufficient.

These objects and other advantageous ends I attain as hereinafter set forth, reference being had to the accompanying drawings, in which,

Fig. 1 is a plan of a portion of an inclined underfeed stoker embodying a simple form of my invention; and

Fig. 2 is a longitudinal vertical section on the line 2—2, Fig. 1.

In the above drawings, 1 represents a portion of the wind box of a stoker of the inclined underfeed type, supplied by air under pressure from a suitable source 2. Fuel is delivered by suitable means, forming no part of the present invention, to a series of parallel retorts 3 which are alternated with series of tuyères 4, supplied with air from the wind box 1. To the rear of the wind box 1 and adjacent the rear ends of the retorts and series of tuyères, is a line of plates 5, the front ends of which fit under suitable transversely extending plates 6 and which are outside and to the rear of the wind box 1.

The plates 5 extend from the plates 6 rearwardly to a series of dumping plates 7. The latter extend transversely of the structure between the lower rear edges of the

plate 6 and a bridge wall (not shown). The dumping plates 7 are pivotally supported on a shaft or spindle 8 and are normally held in their substantial horizontal raised positions by links 9 connected to levers 11 mounted on a suitably supported shaft 12. The shaft 12 is normally locked in the position necessary to maintain the dumping plates raised and is controlled in any suitable manner to permit the plates 7 to swing down and deposit the ashes in a pit 13.

According to my invention, the plates 5 comprise a series of movable dead plates 14 which are positioned in line with the rows of tuyères 4 and reciprocated by means of rods 15. Thus, fuel in direct alignment with the series of tuyères 4 is positively fed toward the dumping plates 7 independently of the action of the rams (not shown) in the retorts 3.

A plurality of stationary extension grates 16 are positioned intermediate the movable dead plates 14 in alignment with the retorts 3, as shown in Fig. 1. Air may be supplied to the stationary grates 16 as illustrated in Fig. 2 through openings 17 in a wall 18 of the air box 1,—the amount of air being controlled by a damper 19 having an operating rod 21 extending to the front of the stoker. The stationary grate structures 16 may be provided with air delivery openings 22.

With the construction as above described, the bodies of fuel in line with the series of tuyères 4 and therefore requiring for their movement abnormal pressure upon the rams (not shown) are assisted in their rearward movement by the plate sections 14, while those portions of the fuel in line with the retorts 3 which are moved by reason of the direct action of said rams and hence might not be completely burned owing to the relatively rapid movement, are supplied with air through the openings 22 of the stationary grates 16, which insure that such fuel shall be completely consumed.

While I have shown only one embodiment of my invention, for the purpose of describing the same and illustrating its principles of construction and operation, it is apparent that various changes and modification may be made therein without departing from the spirit of my invention and I desire, therefore, that only such limitations shall be imposed thereon as are indicated in the ap-

pended claims or as are demanded by the prior art.

I claim:

1. The combination in an inclined underfeed stoker of retorts; lines of tuyères alternated with said retorts; alternated imperforate extension plate sections and stationary grates contiguous to said tuyères and retorts, respectively; and means for moving said extension plates.
2. The combination in an inclined underfeed stoker of retorts; lines of tuyères alternated with said retorts; dead plate sections in the lines of the respective tuyères; stationary grates in line with the respective retorts; means for moving the dead plates in the lines of the respective tuyères; and means for supplying air under pressure to the stationary grates.
3. The combination in an inclined underfeed stoker of retorts; series of tuyères alternated with said retorts; stationary grates respectively in line with said retorts; and movable dead plates respectively in line with said tuyères.
4. The combination in an inclined underfeed stoker of retorts; series of tuyères alternated with the retorts; a movable dead plate operatively associated with each series of tuyères for feeding rearwardly the fuel in line therewith; and stationary fuel support-

ing structures respectively in line with the retorts.

5. The combination in an inclined underfeed stoker of retorts; series of tuyères alternated with the retorts; a movable dead plate operatively associated with each series of tuyères for feeding rearwardly the fuel in line therewith; means for supplying air under pressure to fuel in line with and to the rear of the retorts; and means including grate structures for cutting off air from the fuel in line with and to the rear of the retorts to a desired extent.

6. The combination in a multiple retort underfeed stoker of alternated retorts and tuyères; dead plates in line with the tuyères respectively; grates respectively in line with the retorts; means for moving the dead plates; and means for supplying air under pressure to the grates.

7. The combination in a stoker of retorts placed side by side; tuyères positioned between said retorts; alternated dead plates and open grates extending across the stoker at the rear of the retorts, the grates being stationary and the dead plates movable; means for supplying air under pressure to the tuyères, dead plates and grates; and damper means for controlling the supply of air to the grates.

MAXWELL ALPERN.
